DESIGN FOR A SPOON OR OTHER ARTICLE OF FLATWARE

Alfred G. Kintz, Wallingford, and Frederick W. Stark, Meriden, Conn., assignors to International Silver Company, Meriden, Conn., a corporation of New Jersey

Application January 25, 1935, Serial No. 55,072

Term of patent 14 years

To all whom it may concern:

Be it known that we, Alfred G. Kintz and Frederick W. Stark, citizens of the United States, residing, respectively, at Wallingford, county of New Haven, State of Connecticut, and Meriden, county of New Haven, State of Connecticut, have invented a new, original, and ornamental Design for a Spoon or Other Article of Flatware, of which the following is a specification, reference being had to the accompanying drawing, forming a part thereof.

Fig. 1 is a front elevation of a spoon showing our new design; and

Fig. 2 is a sectional view taken on the lines 2—2 of Fig. 1.

The back of the spoon conforms with the disclosure of Fig. 2, and may be plain or have surface ornamentation embodying the motif disclosed in Fig. 1.

The design is intended for use on sets comprising spoons, forks, knives and similar articles of table-ware.

We claim:

The ornamental design for a spoon or other article of flatware, substantially as shown and described.

ALFRED G. KINTZ.
FREDERICK W. STARK.
